United States Patent Office.

AMÉDÉE PAILLARD, OF ST. CROIX, SWITZERLAND, ASSIGNOR TO M. L. PAILLARD & CO., OF NEW YORK CITY.

Letters Patent No. 105,972, dated August 2, 1870.

IMPROVEMENT IN MUSICAL BOXES.

The Schedule referred to in these Letters Patent and making part of the same.

I, AMÉDÉE PAILLARD, of St. Croix, Canton de Vaud, Switzerland, have invented certain new and useful Improvements in Musical Instruments, of which the following is a specification.

Nature and Objects of the Invention.

My invention relates to that class of instruments commonly known as music-boxes, in which the melodies are produced by a cylinder or barrel rotated by means of a coil spring, and studded upon its circumference with pins, so arranged in relation to a metallic comb that the pins will strike against the graduated teeth or tongues of the comb and produce the required musical vibrations. In all these instruments, so far known to me, a single cylinder or barrel is employed, and the number of tunes or melodies is necessarily limited.

The design of my invention is the production of such improvements as will remove this objection, and render an instrument capable of many changes in the tunes or melodies, with but slight additional expense in its construction; and.

It consists in a novel combination and arrangement of parts, as will be hereafter more fully set forth.

Description of the Drawing.

Figure 1 is a front elevation of the frame of an instrument, removed from the box in which it is usually inclosed, showing the arrangement of the parts composing my invention.

Figure 2 is a plan or top view of the same.

Figure 3 is a vertical transverse section through the plane *x y*, fig. 1.

Figure 4 is a similar section, taken in a plane immediately behind and parallel with the bevel-gear *M*.

Figure 5 is an end view taken from the right-hand end of fig. 1.

General Description.

The rectangular frame *A* supports the various operative parts of the instrument, and has secured to it at either end two journal-boxes, *a a*, in which the shaft *C* has its bearings.

The two disks, *B B'*, secured upon this shaft, furnish the bearings for the journals of the cylinders or barrels *D*, which are arranged between the disks at equal distances apart.

Each cylinder has a disk, *E*, secured upon the end of one journal, provided with a wrist-pin, *f*, and so arranged that it will revolve with the slotted disk *e*, when it is in such position that the wrist-pin is held in the upper part of the curved slot, as illustrated in the sectional view, fig 3.

The disk *e* is operated by the toothed wheel *d*, figs. 2 and 5, which is keyed to its shaft *c*, and which is

driven by the train of wheels and coil spring, that are generally employed in these instruments to give motion to the cylinder.

The cylinders that are not in position to be rotated by the disk *e* are held at rest in proper position, and prevented from turning accidentally by the spring detents *p* screwed upon the disk *B*, each detent having a tooth, *r*, which catches into a hole in the face-plate upon the end of the cylinder.

Each detent is withdrawn and held back from the cylinder, at the proper time, by the stop *P*, secured upon the frame, so that the cylinder thus released is free to rotate with the disk *e*, with which it is in co-operative relation; the end of each spring *p* projects beyond the cylinder a sufficient distance to insure of its striking against and being held by the cam-surface of the stop.

The main shaft *C*, which supports the cylinders, is revolved by means of the vertical shaft *K*, supported in the frame *L*.

The pinion *k* upon this shaft gears with the bevel-wheel *M*, secured upon the end of the main shaft, and is made of such proportion that it makes three revolutions to one of the bevel-wheel *M*.

A second pinion, *n*, upon the shaft *K*, drives the gear *m*, upon which the dial-plate *N* is secured, and makes three revolutions, also, to one of the wheel *m*, so that the revolutions of the two gears, *M* and *N*, driven by the vertical shaft, are identical.

The surface of the dial *N* is marked at regular intervals with numerals, commencing with number one, to designate the number of cylinders in the instrument, and an index, *o*, secured above the dial, upon a stud which passes through the gear *m*, and serves as a pivot for the same, is so adjusted that it designates upon the dial the number of the cylinder that is in operation.

The cover of the case in which the instrument is inclosed is provided with a list descriptive of the melodies performed by the instrument, and showing also what particular airs are performed by each cylinder, so that, by referring to the dial, the number of the cylinder in play, and the tunes performed by it, can be quickly ascertained; and, also, any desired airs of those performed by the instrument may be produced at pleasure by turning the handle *O* forward until the index *o* indicates upon the dial-plate the number of that cylinder upon which the required airs are arranged.

A spring, *F*, secured to the frame *A*, fig. 2, is so arranged that its end presses against the circumference of the disk *B*, and catches into the notches *b*, for the purpose of holding the main shaft *C* firmly in the proper position to prevent the cylinder in operation from moving accidentally out of place, with reference to the disk *e* and comb *X*.

This spring is released from the disk by pressing the handle Q, upon the lever H, down sufficiently to permit the end i of the weighted elbow-lever I to drop under and hold up the arm G, secured to and projecting from the side of the spring F.

By turning the handle O forward, while the lever I is holding up the spring, the shaft C may be turned to bring the next cylinder in play; the disks B B' will then revolve, carrying the cylinders until the next notch b comes under the end of the spring F, when one of the pins, g, upon the inner face of the bevel-wheel M, strikes against the lower end of the elbow-lever I and raises it high enough to withdraw the end i from beneath the arm G, and allow the spring F to drop into the notch b.

The pins g, fig. 1, upon the face of the bevel-wheel M, are arranged in a circle tangent to the end of the elbow-lever I, and are so adjusted that they will trip the lever and release the spring F at the proper time, the number of pins employed being equal to the number of cylinders in the instrument, and, consequently, to the number of tunes it is required to trip the lever I and release the spring F.

The spring lever S is provided with a tooth, t, and is so arranged upon the frame with relation to the disk T, fast upon the main shaft C, that it holds and prevents the shaft from turning except when the slotted disk e is in proper position for the pin f of the next cylinder to enter the slot. At this moment the end of the lever S is raised by the pin u upon the circumference of the disk e, and the disk T is free to revolve, so that the shaft C can only be rotated when the disk e is in the position shown in fig. 5.

As the wrist-pin f cannot be released from the curved slot in the disk e until the latter has made one entire revolution, and the cylinder is in the same position in which it was at the time the wrist-pin f entered the slot, and the tooth r of the spring p was drawn back by the action of the stop P, it follows that, when the spring p is released from the stop, the hole in the face-plate upon the end of the cylinder will be in position to allow the tooth r to readily enter it.

The vertical shaft K is prevented from being turned in the wrong direction by the ratchet-wheel q and a spring pawl pivoted to the frame L.

The cylinders D are shifted laterally between their bearings, to effect the change of tunes, in the manner and by the means that are commonly employed in constructing these instruments.

Claims.

What I claim as my invention is—

1. A series of cylinders arranged upon a rotating shaft, in combination with the comb X, so that each cylinder in turn may be brought into co-operation with the comb, thereby making the instrument capable of producing a variety of tunes or melodies, substantially as described and specified.

2. Operating the series of cylinders by means of the wrist-pins f and slotted disk e, substantially as described and specified.

3. The combination, with the cylinders, of the spring detents p, to lock the cylinders in proper position for the wrist-pins f to enter the slotted disk e, as the cylinders are rotated upon the shaft C, substantially as described and specified.

4. The cam-stop P, for liberating the detents p from the cylinders, substantially as described and specified.

5. The combination and arrangement of the lever H, weighted lever I, arm G, and pins g, for operating the spring-catch F, substantially as described and specified.

6. The mechanism for rotating the cylinders around the shaft C, consisting of the vertical shaft K, pinion k, and bevel-wheel M, in combination with the gear m and pinion n, for operating the dial-plate, in the manner substantially as described and specified.

7. The indicating mechanism N o, constructed substantially as and for the purpose described and specified.

8. The combination, with the disk T upon the main shaft C, of the spring lever S and cam-pin u, arranged and operating in the manner substantially as described and specified.
